UNITED STATES PATENT OFFICE

102,049

DESIGN FOR A PENCIL

Albert L. Davis, Watertown, Conn., assignor to Wallace Pencil Company, St. Louis County, Mo., a corporation of Missouri

Application September 21, 1936, Serial No. 64,943

Term of patent 14 years

To all whom it may concern:

Be it known that I, Albert L. Davis, a citizen of the United States and a resident of Watertown, in the county of Litchfield and State of Connecticut, have invented a new, original, and ornamental Design for a Pencil, of which the following is a specification, reference being had to the accompanying drawing, forming part thereof.

Fig. 1 is an elevational view of a pencil showing my new design; and

Fig. 2 is an enlarged view of the ferrule.

The dominant feature of the design resides in the ferrule shown in full lines.

I claim:

The ornamental design for a pencil, as shown and described.

ALBERT L. DAVIS.
